CLAIM

The ornamental design for a hockey stick rack, as shown and described.

DESCRIPTION

FIG. 1 is an isometric view of a hockey stick rack showing the new design.

FIG. 2 is a front view of the hockey stick rack in FIG. 1.

FIG. 3 is a back view of the hockey stick rack in FIG. 1.

FIG. 4 is a right side view of the hockey stick rack in FIG. 1.

FIG. 5 is a left side view of the hockey stick rack in FIG. 1.

FIG. 6 is an enlarged top view of the hockey stick rack in FIG. 1.

FIG. 7 is an enlarged bottom view of the hockey stick rack in FIG. 1.

FIG. 8 is an isometric view of a hockey stick rack showing the new design.

FIG. 9 is a front view of the hockey stick rack in FIG. 8.

FIG. 10 is a back view of the hockey stick rack in FIG. 8.

FIG. 11 is a right side view of the hockey stick rack in FIG. 8.

FIG. 12 is a left side view of the hockey stick rack in FIG. 8.

FIG. 13 is an enlarged top view of the hockey stick rack in FIG. 8; and,

FIG. 14 is an enlarged bottom view of the hockey stick rack in FIG. 8.

The details shown in broken lines illustrate portions of the hockey stick rack that form no part of the claimed design.

1 Claim, 12 Drawing Sheets
